[57] CLAIM

The ornamental design for a combined condiment shaker set and tray therefor, as shown and described.

DESCRIPTION

FIG. 1 is a front elevation of the combined condiment shaker set and tray therefor, embodying my new design;

FIG. 2 is a rear view thereof;

FIG. 3 is a top plan view thereof; and

FIG. 4 is an end view thereof.

The bottom of the design is flat and unornamented.
